ATTORNEY

UNITED STATES PATENT OFFICE.

MARY GOLDSMITH, OF ST. LOUIS, MISSOURI.

DESIGN FOR A COMBINED CULINARY MASHER AND SPOON.

58,223.

Specification for Design.

Patented June 28, 1921.

Application filed November 11, 1920. Serial No. 423,498. Term of patent 14 years.

To all whom it may concern:

Be it known that I, MARY GOLDSMITH, a citizen of the United States, residing at St. Louis, in the State of Missouri, have invented a new, original, and ornamental Design for a Combined Culinary Masher and Spoon, of which the following is a specification, reference being had to the accompanying drawing, forming a part hereof, in which—

Figure 1 is a top plan view of the com-

bined culinary masher and spoon, showing my design, and

Fig. 2 is a side elevation of same.

I claim:—

The ornamental design for a combined culinary masher and spoon, as shown.

MRS. MARY GOLDSMITH.

Witnesses:

IDA PHILLIPS,

JOHN C. HIGDON.
